[57] **CLAIM**

The ornamental design for a tool carrier, as shown and described.

DESCRIPTION

FIG. 1 is a perspective view of a tool carrier showing my new design;

FIG. 2 is another perspective view thereof;

FIG. 3 is a top plan view thereof;

FIG. 4 is a right side elevational view, the opposite side being a mirror image thereof;

FIG. 5 is a front elevational view thereof;

FIG. 6 is a rear elevational view thereof;

FIG. 7 is a cross-sectional view thereof taken along line 7—7 in FIG. 5, and

FIG. 8 is a bottom plan view thereof.

*Fig. 1.**Fig. 2.**Fig. 3.**Fig. 4.*Fig. 5.

Fig. 6.

Fig. 7.
